UNITED STATES PATENT OFFICE.

WALTER N. CRAFTS, OF OBERLIN, OHIO.

ELECTRIC FURNACE.

1,070,017.

Specification of Letters Patent. Patented Aug. 12, 1913.

Application filed December 4, 1911. Serial No. 663,860.

To all whom it may concern:

Be it known that I, WALTER N. CRAFTS, a citizen of the United States, residing at Oberlin, in the county of Lorain and State 5 of Ohio, have invented a certain new and useful Improvement in Electric Furnaces, of which the following is a full, clear, and exact description, reference being had to the accompanying drawings.

10 This invention relates to furnaces of the shaft or "Hochofen" type, the object of the invention being to provide such a furnace with means for heating the contents by electric induction acting on a fused bath at the 15 base of the shaft, heat from which bath, rising in the shaft, causes chemical reactions in the contents thereof.

My furnace may accordingly be constructed as to shape somewhat along the lines of 20 the modern blast furnace, and a blast may be employed or not, as desired, while below the shaft I provide a basin adapted to hold the molten bath, and I provide a magnetic core and a primary winding so positioned 25 with reference to the basin that at least some portion of the bath may be included in the secondary circuit and be thereby fused. In my preferred form this secondary circuit comprises a portion of the bath within the 30 basin and a conductor outside of the basin, the outside conductor being incompletely annular but forming a complete annular conductor in conjunction with such portion in the basin. The outside portion of the sec- 35 ondary is preferably below the basin connecting with a lower portion of the bath, as this has great advantages in properly circu- 40 lating the metal of the bath, as well as enabling the basin to be of the most desired shape.

The portion of the secondary circuit outside of the basin may consist of fused material, which may bodily circulate during the operation, and constitute a portion of the 45 material of the bath, or it may consist of a solid conductor of greater electric conductivity than the portion of the annular secondary within the bath, in which case the external portion will not fuse. My prior 50 application #657,270, filed October 28, 1911 shows and claims a furnace employing such external portion of the secondary broadly, whether it is fusible or of material not fused. My application #662,822, filed No- 55 vember 28, 1911, covers the employment of the external portion of different material

and not fused. The present application relates to furnaces of the shaft type including either form of arranging the secondary.

The drawing clearly illustrates my invention embodied in a shaft furnace having the completely-fused bodily-circulating secondaries.

Figure 1 is a vertical central section of such furnace; Fig. 2 is a horizontal section, 65 as indicated by the line 2-2 of Fig. 1.

Referring to the parts shown by numerals, 10 indicates the base portion of the furnace, 11 the basin therein adapted to carry an open bath designated 12. This basin consists of an unrestricted continuous hearth in which the material may collect and from which it may be tapped without destroying the secondary circuit hereinafter referred to. Above the basin the walls continue upwardly for some distance and then are arched or continued inwardly, as shown at 14. Extending upwardly from these arches is the shaft 16 communicating with the basin chamber through the somewhat restricted 70 opening 17. Near the upper end of the shaft is provided the usual charging bell 18. The drawing shows also a fan and piping 19 for the extraction of furnace gases, and shows a twyer 20, which may be employed, if de- 75 sired.

Extending through the body 10 and beneath the basin I show a pair of incomplete tubes 25 open at their ends. Occupying these tubes are magnetic laminated cores 26 90 connected at their ends by yoke pieces 27 supported on suitable brackets 28. Around the yokes 26 are primary windings 30. In the body outside of the tubes 25 are the secondaries connecting with the material in the 95 bath, which will now be described.

In the embodiment shown in the drawing, I have formed in the body 10, in a central vertical plane of the furnace, U-shaped passageways extending about the two tubes 25, 100 spaced therefrom and terminating at their upper ends at the bottom of the basin. Each of these passageways has an outer leg 35 and an inner leg 36. The two inner legs, however, are preferably merged into one 105 common leg, as shown. The outer and inner legs having their three upper ends terminating at the bottom of the basin, the material in the basin is in electric communication with the material in the U-shaped pas- 110 sageways.

In starting my furnace, the passageways

35 and 36 in the lower portion of the bath are filled with conducting material. This may be accomplished either by running in molten metal or by filling the passageways and bottom of the bath with chips or filings. 5 The shaft is charged in the usual manner with ore, coke or charcoal and suitable flux, as limestone. When the furnace is charged to the desired extent, alternating current is passed through the primary windings. This, by induction, heats the annular secondaries to the fusing point. The fused material in the bath circulates with the other material and soon the whole bath is molten. This circulation is increased by having the central leg 36 in the passageways of different area than the sum of the other two (as shown in the drawings), so that the heating is different and the secondaries bodily circulate. 10 15 20 25 30 35 40

In operation, the electrically generated heat rising from the molten bath through the mass of material in the shaft causes the carbon of the charge to unite with the oxygen of the ore and the calcium to unite with the silica and other ingredients of the ore in the usual manner. Accordingly, the molten metal and slag continue to descend into the bath chamber as new material is supplied at the bell. The slag is tapped off, whenever desired, through a suitable slag tap 40, and the molten metal is run out through the tap hole 41. At the end of the campaign the material in the passageways 35 and 36 is run out through the normally plugged passageway 42. If desired, a blast may be employed in addition to the electric heat. Such blast may be advantageous, particularly in starting the operation, though it is frequently preferable to have no admitted air.

My furnace, by obtaining the heat principally or entirely from the induction coils, much reduces the coke or charcoal employed in the shaft, for the carbon need be only sufficient, when no blast is employed, to combine with the oxygen of the ore. When a blast is employed, it will deliver considerably less air than the usual blast, with corresponding diminution in the carbon which must be supplied to combine with the oxygen of the air.

My furnace not only may make better pigs, by reason of the elimination or reduction of air-oxygen and the consequent reduction of carbon employed, but it may produce steel direct, instead of pig iron, because the molten metal, with a comparatively high carbon content, descending from the shaft into the bath, may be refined by some of the ore also descending into the bath, the oxygen of such ore combining with some of the carbon content to leave a resulting metal of proper carbon content for steel.

By reason of the possibility in my furnace of maintaining the heat without blast, I can

eliminate troublesome oxygen or nitrogen compounds which occur with the ordinary blast furnace operation.

Having thus described my invention, what I claim is:

1. In an electric furnace, the combination, with a shaft adapted to contain material descending by gravity, of an induction coil adjacent to the base of the shaft and having an annular secondary, a portion of which comprises material in a continuous fused bath into which the shaft discharges and the rest of which is below such bath. 70 75

2. In an electric furnace, the combination of a basin, a shaft above the basin discharging thereinto, and an induction coil having a substantially horizontal closed magnetic core, one or more primary windings therefor and an annular secondary, at least a portion of which comprises material in the basin and the rest of which is below the basin. 80 85

3. In an electric furnace, the combination of a basin, a shaft above the basin, means for controlling the entrance to the shaft near its upper end, and an induction coil having an annular secondary, a portion of which comprises material within the basin and a portion of which is exterior of and lower than the basin, the basin being provided with means enabling it to be tapped without destroying the secondary circuit. 90 95

4. In an electric furnace, the combination, with a shaft and a basin below it provided with a tap for metal, of means for heating 100 by electric induction the material in the bath, the heat rising from such bath into the shaft, said means comprising a substantially horizontal annular core, a primary winding and an annular secondary, a portion of 105 which consists of molten metal in the basin above the metal tap and the rest of which consists of a U-shaped conductor not destroyed by the tapping operation.

5. In an electric furnace, the combination, 110 with a shaft, of a basin below it, an induction coil having a substantially horizontal closed magnetic core, primary windings about the legs of the core, and an annular secondary composed of a portion of the bath 115 and a multiple U-shaped conductor extending about the primary outside of the bath, said basin providing a receptacle in which the material may collect and from which it may be tapped without destroying the secondary circuit. 120

6. In an electric furnace, the combination of a shaft, a basin below the shaft in which the molten metal from it may collect, a U-shaped passageway for material below the 125 basin which has its upper ends in communication with the bottom portion of the basin, a substantially horizontal closed magnetic core having a leg lying between the arms of said passageway, a primary winding on 130

said core, and means for tapping molten metal from the basin without destroying the annular secondary which is provided by the U-shaped passageway and a portion of the 5 molten metal in the basin.

7. In an electric furnace, the combination of a shaft, a basin below the shaft in which molten metal from the shaft may collect, a plurality of U-shaped passageways having 10 their adjacent legs in common and lying in a substantially vertical plane, a substantially

horizontal closed magnetic core having legs lying between the arms of the passageways, and primary windings for said core surrounding said legs.

In testimony whereof, I hereunto affix my signature in the presence of two witnesses.

WALTER N. CRAFTS.
